UNITED STATES PATENT OFFICE.

JOSEPH O. BALDA, OF NEWARK, OHIO, ASSIGNOR TO CENTRAL GLASS WORKS, OF WHEELING, WEST VIRGINIA, A CORPORATION OF WEST VIRGINIA.

DESIGN FOR A GLASS GOBLET OR SIMILAR ARTICLE.

55,358.

Specification for Design.

Patented June 1, 1920.

Application filed January 2, 1920. Serial No. 349,066. Term of patent 14 years.

To all whom it may concern:

Be it known that I, JOSEPH O. BALDA, a citizen of Hungary, and resident of Newark, county of Licking, and State of Ohio, have invented a new, original, and ornamental Design for a Glass Goblet or Similar Article, of which the following is a specification, reference being had to the accompanying drawings, in which—

The figure is a side elevation of a goblet, showing my new design.

I claim:

The ornamental design for a glass goblet or similar article, as shown.

In testimony whereof I affix my signature in presence of two witnesses.

JOSEPH O. BALDA.

Witnesses:

H. J. ALEXANDER,
J. N. PUGH.
